Primary Examiner — Mehri F Bajoul(74) *Attorney, Agent, or Firm* — Malloy & Malloy, P.L.; Robert M. Downey(57) **CLAIM**

The ornamental design for a basketball apparatus, as shown and described.

DESCRIPTION

FIG. 1 is a top, front perspective view of a basketball apparatus showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines in the drawings depict portions of the basketball apparatus that form no part of the claimed design.

1 Claim, 7 Drawing Sheets(56)
